[57] CLAIM

The ornamental design for a combined portable printer, sheet feeder and base, as shown and described.

DESCRIPTION

FIG. 1 is a front, top and right side perspective view of the printer shown in FIG. 3;

FIG. 2 is a rear bottom and left side perspective view of the printer shown in FIG. 3;

FIG. 3 is a top front and left side perspective view for a combined portable printer, sheet feeder and base showing my new design;

FIG. 4 is a top rear and right side perspective view thereof;

FIG. 5 is a bottom perspective view thereof;

FIG. 6 is a right side elevational view thereof, the left side can be seen in FIG. 10;

FIG. 7 is a front elevational view thereof;

FIG. 8 is a rear elevational view thereof;

FIG. 9 is a front perspective view of the printer and sheet feeder in an operational mode in which the paper access hatch is open 180° and the paper support arms are in their open or operational positions;

FIG. 10 is a rear perspective view of FIG. 9;

FIG. 11 is a front perspective view thereof;

FIG. 12 is a right side elevational view of the printer and sheet feeder in an operational mode;

FIG. 13 is an exploded perspective view thereof;

FIG. 14 is a perspective of the printer and base;

FIG. 15 is a perspective view of the paper access hatch with the paper support arms in their closed or nested positions;

FIG. 16 is a perspective view of the paper access hatch with the paper support arms in their open or operational positions; and,

FIG. 17 is a top perspective view of the base, the bottom can be seen in FIG. 5.
